FIG. 17 is a left side elevation view of FIG. 15;
FIG. 18 is a right side elevation view of FIG. 15;
FIG. 19 is a top plan view of FIG. 15;
FIG. 20 is a bottom plan view of FIG. 15;
FIG. 21 is a front, right, and top perspective view of FIG. 15;
FIG. 22 is a front elevation view of a LED controller,
showing a fourth embodiment of our new design;
FIG. 23 is a rear elevation view of FIG. 22;
FIG. 24 is a left side elevation view of FIG. 22;
FIG. 25 is a right side elevation view of FIG. 22;
FIG. 26 is a top plan view of FIG. 22;
FIG. 27 is a bottom plan view of FIG. 22;
FIG. 28 is a front, right, and top perspective view of FIG. 22;

FIG. 29 is a front elevation view of a LED controller,
showing a fifth embodiment of our new design;
FIG. 30 is a rear elevation view of FIG. 29;
FIG. 31 is a left side elevation view of FIG. 29;
FIG. 32 is a right side elevation view of FIG. 29;
FIG. 33 is a top plan view of FIG. 29;
FIG. 34 is a bottom plan view of FIG. 29;
FIG. 35 is a front, right, and top perspective view of FIG. 29;
FIG. 36 is a front elevation view of a LED controller,
showing a sixth embodiment of our new design;
FIG. 37 is a rear elevation view of FIG. 36;
FIG. 38 is a left side elevation view of FIG. 36;
FIG. 39 is a right side elevation view of FIG. 36;
FIG. 40 is a top plan view of FIG. 36;
